UNITED STATES PATENT OFFICE

2,457,630

METHOD OF MANUFACTURING FULLED OR HARDENED FELT ARTICLES SUCH AS FELT BOOTS OR FOOTWEAR

Geoffrey Harley Beetson, Hudcar Mills, Bury, England, assignor to The Bury Felt Manufacturing Company Limited, Bury, England

Application October 16, 1945; Serial No. 622,547
In Great Britain March 26, 1945.

1 Claim. (Cl. 12—142)

1

This invention relates to an improved method of manufacturing fulled or hardened felt articles such as felt boots or footwear, and is particularly but not exclusively applicable to unlaced high felt boots reaching to the knee.

The invention comprises the method of manufacture of fulled or hardened felt articles having at least one joint including the step wherein a felt blank is produced which is hardened in a defined shaped area so as to leave an unhardened or unfelted margin, which margin is subsequently hardened or felted in the production of the joint.

Such method may include the further step wherein the said margin is thinned and the joint is made by overlapping and/or by the superimposition of additional feltable fibres.

The invention for the manufacture of a felt boot comprises the steps wherein a predetermined blank form is partially hardened in a fibrous batt and having a defined hardened area with unhardened margin which blank or form is then folded together into boot shape, the heel, sole, front of leg, top of foot and toe being joined by utilising the fleecy or unhardened margins with or without wads capable of intermingling at the point of juncture and submitting these to felting actions, the felt boot being further felted and further treated as may be required in manner set forth.

The accompanying drawings illustrate one example of the invention as applied to the manufacture of a felted boot, in which Fig. 1 shows the shape of a hardener plate or pattern for making a single impression of a definite shape in a soft batt in the felting or hardening of the same.

Fig. 2 shows a suitable lay-out for a plurality of hardener plates or patterns;

Fig. 3 shows a finished blank produced by the plate or pattern of Fig. 1;

Fig. 4 shows means for finishing the heel;

Fig. 5 shows the formation of the joint in the sole.

Fig. 6 shows an alternative lay-out for a plurality of hardener plates or patterns.

Fig. 7 shows an alternative blank similar to Fig. 3, and produced by a pattern or hardener plate of the lay-out shown in Fig. 6.

The process consists in taking a soft batt of fibers composed partly or mainly of wool or animal hairs or other fibrous material, which may felt or commingle under the influence of heat, steam and jiggling, and forming in said soft batt in a felting or hardening machine a felt blank of a definite shape provided with an unhardened or unfelted margin and composed of a leg por-

2

tion and half foot portions extending from opposite sides of the leg portion at one end thereof. The leg portion is folded into cylindrical form with its unhardened or unfelted longitudinal margins overlapping each other at the front, thereby bringing the foot portions into parallel disposition at one end of the cylindrical leg portion, with the complementary unhardened or unfelted margins of said foot portions also overlapping.

10 The hardening or felting of the soft batt to produce said felt blank is effected by placing the soft felt batt upon a bottom flat plate of the felting or hardening machine in which the upper plate is provided with one or more patterns 10 of the form illustrated in Fig. 1 of the drawings. When more than one pattern is employed, the preferred arrangement is the lay-out illustrated in Fig. 2 of the drawings and the arrangement is such that a margin of unfelted or unhardened fibers is left on three sides of each hardened area. Each pattern produces in the soft felt batt a hardened area of definite shape which has on three of its sides the said unfelted margin. Each pattern forms a raised portion on the under side of the upper plate and forms an impression in the soft batt during the hardening or felting of the definite shaped areas. The pattern, or patterns, may be covered by canvas or other covering material, or not covered, 20 and may be of wood, metal, or any rigid material in which the surface contacting the fleece may be rough or smooth. When hardening is carried out in a known manner, using steam, pressure and jiggling or by other known means, only that part of the fleece under the patterned shapes is hardened, while the remainder remains substantially unfelted, although the marginal area around the hardened shapes patterned on the batt will have been subjected to temperature and humidity, and even to some pressure, so that the fibers will be 30 sufficiently interlaced or matted together to permit subsequent handling.

Following the hardening or preliminary felting treatment, the hardened batt is cut into "boot shapes" by cutting around and outside the hardened parts of the batt, leaving a margin of unhardened material on at least three sides of the shape as illustrated at b in Fig. 3. This margin of unhardened fibres may be thinned until one half remains; this thinning may be facilitated and assisted by forming the original batt from two separate batts of carded fibres.

At this stage the heel of the boot or footwear is formed by folding together the hardened batt 55 11 over a rose 12 supplied with steam, the trimmed

unhardened edges being arranged as indicated at 13, small strips of fleece or sliver being added as need be, and hardening or felting the same by the action of a co-operating, jiggling or vibrating tip hardener as illustrated at 14 Fig. 4, or by similar means whereby the previously unhardened fibres mingle and felt together and the joint corresponds with the remainder of the material.

Next the sole is formed by continuing the heel junction and placing the margins forming the sole joint, in overlapping relation with any additional fleece or sliver which may be needed, on a steam heated plate 15 and subjecting it to the jiggling or oscillating action of a strip hardener 16 as illustrated by Fig. 5, or by similar means.

The front edges b of the boot or footwear are now brought together, while a non-feltable filler is placed inside the leg portion to prevent undesired adhesion, and the leg section is subjected, with the addition to the seam of any fleece or sliver which may be needed, to the action of a small plate hardener (not shown) by known means so that the leg portion of the boot is formed in hardened fleece. A tendency to gape at the front of the angle may be prevented by the inclusion of an extra flap of unhardened fleece when cutting out the shape, as shown by part a in Fig. 3.

Formation of the upper side of the foot is brought about in a similar manner to that employed for the foot, a non-feltable filler being inserted and the foot submitted, with the addition to the seam of any sliver which may be needed, to the action of a small plate hardener.

Completion of the boot or footwear is achieved by slipping the leg and foot over the rose employed to form the heel, together with small strips of fleece or web as may be desired and hardening or felting the same by the action of a co-operating, jiggling or vibrating tip hardener as illustrated by Fig. 4, or by similar means, whereby the jointed toe portion felts together to correspond with the remainder of the material.

Figs. 6 and 7 show a slightly modified lay-out for a multiple impression and a slightly different shape of blank compared with Figs. 2 and 3.

Further hardening action may be imposed upon all or any parts of the boot shape at this stage, which may be followed by felting or milling action by known means to produce the desired hardness or finish.

If desired, the boot shape may be dyed, proofed or stiffened by known means at any stage after the jointing has been carried out, or the boot or footwear may be made from dyed and/or treated fibres.

Moreover the boot shape may be treated with plastic material and submitted to felting action or shrinkage in order to produce an imitation leather appearance as described in the specifica-

tion of the U. S. application for patent, Serial No. 570,224.

Subsequently, the boot so far processed can be stretched on a built-up last of approximately the desired shape, steamed and then dried. It can be placed upon a contoured or modelled collapsible or rigid former which may be hollow and submitted to further steaming if need be from the interior and exterior. Moreover the boot shape may be moulded, fashioned or beaten by the action of hammers.

It will be understood that the boot may have a rubber or other sole if desired and could be coated on its exterior surface with rubber, synthetic rubber or any suitable composition of a plastic nature.

Modifications of the described method of manufacture may be made, for instance the sequence of forming the joints may be altered and the hardening together of the fleece joint may be assisted by sewing them together with woollen or other yarns. Furthermore the boot shape felt blank produced by the pattern illustrated in Fig. 1 may be formed from two or more sections of hardened fleece which have been previously joined together in a manner similar to that described in this application. Reinforcement may be given to any part of the boot or footwear by incorporating additional fleece or sliver by means of hardening action at any convenient stage.

I declare that what I claim is:

The method of manufacturing felt boots which consists in providing a batt of fibrous material having a partially hardened shaped area forming a leg portion and half foot portions extending from opposite sides of the leg portion at one end thereof with an unhardened margin around said portions, folding said leg portion into cylindrical form with its unhardened longitudinal margins overlapping each other at the front and thereby bringing the foot portions into parallel disposition at one end of said cylindrical leg portion with the complementary unhardened margins of said foot portions also overlapping, and subjecting the overlapping edges of the leg and foot portions to the action of a felting machine, thereby to cause said overlapped margins to be felted together.

GEOFFREY HARLEY BEETSON.
